COLOR INDICATION FOR SHUTTLE
CHANGING LOOMSRichard G. Turner, Worcester, Mass., assignor to
Crompton & Knowles Loom Works, Worcester,
Mass., a corporation of MassachusettsApplication May 8, 1934, Serial No. 724,520
Renewed April 2, 1936

14 Claims. (Cl. 139—232)

This invention relates to improvements in multicolor shuttle changing looms and more particularly to the color selecting mechanism therefor.

In a type of multicolor shuttle changing loom heretofore proposed by me there is provided a magazine having two stacks of reserve shuttles to cooperate with a lay arranged to move a shuttle drawn from either stack into action when a weaving shuttle has its supply exhausted. The magazine is so arranged that shuttles drawn from either stack pass into a common compartment from which they move to a shuttle box on the lay, the shuttles from the front stack dropping in the compartment while those of the rear stack are pushed forwardly into it.

The release mechanisms for the two stacks include in their constructions hook shaped depressible controllers which are controlled by the pattern mechanism so that but one controller is operatively relatable at a time to an actuator.

Change boxes are provided on the magazine end of the lay and are called into action by weft detecting mechanism. These boxes rise at the time of change so that the top box receives the reserve shuttle while the bottom box receives the oncoming depleted shuttle, subsequent lowering of the boxes placing the fresh reserve shuttle into picking position while the depleted shuttle is expelled forwardly from the lay.

As heretofore constructed it has been possible to advance a shuttle from the magazine independently of the rising motion of the boxes and it is an important object of my present invention so to coordinate the change box and magazine that it is not possible to release a shuttle from the magazine until assurance is had that the change boxes have started to an elevated position where change can occur. This result I achieve by having a single moving member, such as a lifter lever, actuated at the time a change is called to depress the selected hook and at the same time raise the change box. A single latching device controlled by the detector mechanism rocks the lifter lever and should it fail in its operation the shuttle advancing and change box lifting operation will not be performed.

When the loom is equipped with a Knowles head receiving its indication from a vibrator lever there is the possibility that with high speeds the controller for the hooks will vibrate sufficiently to render uncertain their exact positions with respect to the part which coacts with them to operate the magazine. The movement of the chain balls under the vibrator run is accompanied by a slight fluttering or unsteadiness on the part of the vibrator which is transmitted to the hooks and it is a further object of my invention to provide means for preventing this slight uncertainty in the position of the vibrator lever from being communicated to the color selecting hooks. This

result I may accomplish either by a specially designed chain link or by a lever system interposed between the vibrator and the hook controller and related periodically to a surface which steadies the hook connections.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a front elevation of a loom having my invention applied thereto,

Fig. 2 is a side elevation on an enlarged scale 15 looking in the direction of arrow 2, Fig. 1,

Fig. 3 is a rear elevation of the upper left hand part of Fig. 1, showing a pattern chain adapted to weave a fabric with two picks of one color and two picks of a second color,

Fig. 4 is a detail plan view looking in the direction of arrow 4, Fig. 2,

Fig. 5 is an enlarged detail side elevation of the switch mechanism,

Fig. 6 is an enlarged side elevation of the lower 25 part of Fig. 2,

Fig. 7 is a detailed vertical section on line 7—7 of Fig. 2,

Fig. 8 is a diagrammatic view showing the form of chain which may be used with my invention 30 when weaving a fabric having a stripe of four picks alternating with another stripe of a different kind operating with four picks, and

Fig. 9 shows a form of chain which can be used in carrying out the modified form of my invention. 35

Referring to the drawings, the loom frame 20 supports at the upper left hand end thereof a Knowles head motion K and has a lay L at the left end of which is mounted the shifting shuttle 40 box structure B. At the opposite or right hand end of the loom is a magazine M which in the present instance is arranged to supply reserve shuttles of two distinctive kinds.

As shown in Figs. 1 and 3 the head motion 45 comprises upper and lower cylinders 21 and 22, respectively, between which lie vibrator gears 23 mounted on vibrator levers 24 one each of which is shown. In the preferred form of the invention the vibrator lever may be positioned by the 50 ordinary chain indicated at C as comprising large rolls 25 and sinkers or low rolls 26 which position the run 27 of the vibrator. The vibrator shown controls the drop boxes to be described.

A box lifter rod 30 supports upper and lower 55 shifting shuttle box cells 31 and 32, respectively. The vibrator gear has a connector 29 attached to a box lever 33 from which extends a lifter chain 34 trained around appropriate sheaves and connected to the lifter rod 30, see Fig. 1. It is 60

sufficient for present purposes to state that the rolls on the chain move the vibrator gears into engagement with one or the other of the cylinders to be rotated for the purpose of actuating the lever 33 to raise or lower the shuttle boxes. These connections are old, and may be as more fully set forth in Patent No. 837,284, simplified to operate two shifting boxes.

A fixed stud 35, see Figs. 2 and 6, has secured thereto a bracket 36 on the horizontal arm of which is pivoted a selector lever 37 having a guide head 38. Front and back selector hooks 39 and 40, respectively, pass through the head and are positioned one at a time in the path of a downwardly movable actuator pin 41 carried by a lifter lever 42 movable about the stud 35. A flexible link 43 is attached to the selector lever by an adjustable connection 44 and acts to move the guide head rearwardly, or to the right in Fig. 2, against the action of spring 45. The latter extends between the bracket 36 and the upper part of lever 37, and tends to move the guide head forwardly to place rear hook 40 in the path of actuator pin 41. The guide head can thus be moved to place either hook operatively with respect to the actuator.

The forward arm 47 of lever 42 is adapted for occasional connection with a periodically rocking actuator lever 48 driven normally during loom operation by a cam 49 on the bottom shaft 50 of the loom. A lifter latch 51 is pivoted to lever 48, see Fig. 7, and is connected at its lower end to the core 52 of a solenoid 53 carried by the actuator lever 48. A notched overhang 54 on the forward arm of lifter lever 42 is normally cleared by the latch 51 when the solenoid is deenergized, a light spring 55 holding the latch in normal inoperative position as shown in Fig. 7.

When the solenoid is energized the latch moves under the notched overhang and is held in that position by a hooked spring 56 supported on lever 42. The spring holds the latch in its operating position before the rocking lever starts to rise independently of continued action of the solenoid. When the latch moves up it will free itself from the spring hook and then engage the overhang 54. The sequence of operations is rapid and the latch does not have time to move away from the overhang before engaging it. On the down stroke the latch is free to move back to normal idle position when pulling away from the overhang. The hooked spring is further described and claimed in my copending application Serial No. 585,564.

55 A two part yielding lifter link 58, see Fig. 2, is suspended from the front of lifter lever 42 and is attached to the lower end of a box lifter rod 59 normally in down position. Upper and lower transfer shuttle boxes 60 and 61, respectively, are supported by the upper end of the rod 59. The boxes are similar in their shuttle changing movements to those shown in Patent No. 1,834,302, and in my copending application Serial No. 460,746.

65 The magazine M is arranged to supply reserve shuttles containing two different kinds of weft. A bracket 65 projecting laterally from the loom frame holds the magazine by means of supports 66 extending forwardly from the bracket and 70 attached to inner and outer end plates 67 and 68, respectively. A back wall 69, partition 70, and front wall 71, provide two spaced compartments or guideways for the stacks of reserve shuttles.

75 The bottom shuttle of the rear stack is sup-

ported on a fixed plate 72 immediately in front of a plunger 73 normally in rear position. When hook 39 is depressed, a link 74 connected thereto will rock lever 75 clockwise to advance the plunger toward the front, or left in Fig. 2. The bottom rear shuttle is thereupon moved into a compartment P under the front shuttles and falls on arms 76 secured to and extending rearwardly from the lay. As the latter moves backwardly, the shuttle falls off the arms 76 and into the top 10 box 60, which has been raised to receive it. The plunger is thereafter moved back to normal position by spring 77. This mode of transfer and the arms 76 are set forth and claimed in my copending application Serial No. 560,573. 15

The bottom shuttle of the front stack rests on a finger 78 pivoted on the front magazine wall and held yieldingly in shuttle supporting position. When hook 40 is depressed a link 79 connected to it rocks lever 80 to lift a shorter link 81 attached to the finger 78, removing the latter to permit the lowest front reserve shuttle to fall into the compartment P and on the support arms 76. Transfer to raised box 60 then follows substantially as already described for the rear shuttles.

The superposed front reserve shuttles are held up by a friction pad 82 which presses against the next to the bottom front shuttle to support the stack when the lowest shuttle falls. When finger 78 rocks clockwise, Fig. 2, the pad 82, which is normally held yieldingly forward, is pushed back by spring action to hold the upper shuttles. At transfer the cover 85 of box 60 is raised by rod 59 when the lay moves rearwardly and a lug 86 35 on the cover engages a fixed cam 87 on the magazine to pivot the cover upwardly so the incoming shuttles can enter the box 60.

Lever 115, see Fig. 5, is positioned by the vibrator 24 for the boxes through the connections 40 shown in Figs. 1, 3, and 5, wherein there is illustrated one form of mechanism to maintain the indication free from undesirable vibration as the pattern chain presents successive high rolls under the lever 24. The flexible link 43 is connected to the outer end of lever 115, while there is passing downwardly through a part of said lever a lifting rod 117 the upper end of which is connected to a lever 118 pivoted as at 119 to the head end of the loom. 50

The lever 118 has an arm 120 attached to a link 121 connected to the vibrator lever 24, see Fig. 3. When the vibrator is down rod 117 drops so that an adjustable lifting collar 122 thereon will permit downward movement of the lever 115, and when 55 the vibrator is lifted to the position shown in Fig. 1 by being over a high roll, the rod 117 lifts the lever 115. When lever 115 is down a light spring 111 causes the pole piece 110 of a switch 104 to connect electrodes 103 and 108, but when 60 the lever is up the pole piece is raised by the heavy spring 113 to connect electrodes 106 and 107.

It is desirable that the pole piece maintain its contacts and the lever 37 hold the hooks 39 and 40 without fluttering or unnecessary vibration, so that the circuits and magazine controls may be certain in their action. When employing the usual Knowles head pattern chain I accomplish this result by an additional lever 126 pivoted on fixed stud 116 and having a stop screw 127 held against a stop lug 128 on lever 115 by tension spring 129. The lower end of lever 126 coacts with a cylindrical segment 130 secured to a hub 131 fast on the bottom shaft 50 of the loom. The segment 130 is concentric with the shaft and has 75

an inner surface 133 to position a lug 134 on the lower end of lever 126. The pattern mechanism is so timed with respect to the segment that when one high roll is passing from under the vibrator lever and another is approaching it, a condition which is likely to result in a slight dipping of the vibrator lever, the surface 133 will move by rotation of the bottom shaft into holding relation with respect to the lug 134. Under these conditions levers 115 and 126 are in the dotted line position shown in Fig. 5, with link 43 and spring 113 tensioned. Any downward pull on lever 115 will be transmitted through lug 128, screw 127 and lug 134 to segment 130 and be resisted by the latter to prevent fluttering or shaking of pole piece 110 and selector hooks. The pattern chain is timed so that it moves the vibrator lever upwardly, or permits its descent, during those times when the segment 130 is away from lug 134.

When weaving a so-called 2 and 2 pattern the pattern chain will be built as shown in Fig. 3 and is composed of two low balls 26 alternated with two high balls 25. The segment is operatively related to lever 115 during the time that control of the vibrator lever is passing from one high ball to another high ball, but it is not operative while the vibrator control is passing from a low to a high ball, or vice versa. In other words, segment 130 is operative on alternate beats only, and not on intermediate picks when the vibrator is subject to shift by the pattern chain. This alternate pick relation is obtained by having the segment on the bottom, or two pick, shaft 50.

My invention is not restricted to 2 and 2 weaving, however, and I may weave a fabric having wider bands or stripes, as an example, a 4 and 4 pick weave, where the repeat is eight picks, four weft threads of one color being followed by four threads of a different color. Such a pattern would be woven by the chain assembled as shown in Fig. 8, where a series of four low balls 26 is followed by another series of four high balls 25. The segment 130 will take care of the spaces *m* and *n* between the first and second, and third and fourth high balls, reading left to right in Fig. 8, but it will not operate when the space *S* passes under the vibrator, since this is the point in the chain where a shift of control from high to low or vice versa, would or could occur if the repeat were different.

In order to prevent fluttering at such a time, that is, when space *S* is under the vibrator, I use the form of link shown in Holmes Patent No. 1,953,652 and designated herein at 159. In this way the lever 115 and pole piece are maintained without objectionable vibration throughout the time that the vibrator is under a series of rolls. No serious fluttering occurs when the vibrator is down, since at such times it is likely to rest on a fixed part 149 of the head frame rather than the low balls. At these times there is no need for moving the lug 134 into operative relation with the segment nor is there any force tending to disturb the lever 115, since springs 45 and 111 both act to lower it, and spring 113 is slack.

In the second form of my invention shown in Fig. 9, all the spaces between high rolls may be occupied by the links 159. The upper surfaces of the links are substantially concentric with the axis around which the chain turns when under the vibrator lever, and as a result, lever 115 will be held against objectionable vibration.

From the foregoing it will be seen that I have provided means whereby the oscillation or flut-

tering of the vibrator lever which is normal with the usual type of chain in the Knowles head is prevented from being communicated to those parts which control the color selection and the switch 104. It will be seen that this result is accomplished by a lever which is operatively related to the color selector and switch at those times when the fluttering would result and it will be noted that this control is removed in time to permit the vibrator to move from a high to a low roll or vice versa. It will further be seen that when repeats of four or more successive picks of the same color are being woven I may employ a form of chain link which will supplement the lever action. This is desirable in the type of loom specifically described wherein each weaving shuttle must be active for two successive picks and where a change from one to another weaving shuttle can occur at the end of an even number of picks laid by either shuttle.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom, a set of shifting shuttle boxes to render active or inactive any one of a plurality of weaving shuttles, a vibrator lever, a pattern chain to position the lever, connections between the vibrator lever and the shuttle boxes, multicolor weft replenishing mechanism, a selector for said replenishing mechanism, connections from the vibrator lever and the selector, and means to prevent substantial vibration of the selector when the pattern chain passes under the vibrator lever.

2. In a loom, multicolor weft replenishing mechanism, a color selecting device for the mechanism, a vibrator lever, a pattern chain to move the vibrator lever, a member connected to and movable by the vibrator lever, connections between the member and the selector device, and means connected to the member to prevent substantial vibration of the member and selector mechanism as the pattern chain passes under the vibrator lever.

3. In a loom, multicolor weft replenishing mechanism, a color selector device for the mechanism, a vibrator lever, a series of high and low chain balls to pass under the vibrator lever, a member to be moved by and with the vibrator lever, connections between the member and the color selector effective to give said selector positions varying with the position of the vibrator lever, and means acting in timed relation with the movements of the high balls and operatively related to the member to prevent substantial vibration of the member and color selector when high chain balls pass under the vibrator lever.

4. In a loom, multicolor weft replenishing mechanism, a color selector for said mechanism, a vibrator lever, a series of high and low chain balls to pass under and position the vibrator lever, a regularly moving element, connections between the vibrator lever and the color selector to position the latter, and means operatively interposed between the element and the connections to prevent substantial vibration of the selector when high balls are passing under the vibrator lever.

5. In a loom, a multicolor weft replenishing mechanism, a color selector for the mechanism, a vibrator lever, high and low chain balls to position the vibrator lever, a force transmitting

- lever, a link between the vibrator lever and the force transmitting lever causing the latter to be moved by and with the vibrator lever, a link between the force transmitting lever and the color selector to position the latter according to the position of the vibrator lever, and means operative while the chain balls are passing under the vibrator lever to prevent substantial vibration of the force transmitting lever and the color selector.
6. In a loom, a multicolor weft replenishing mechanism, a color selector for the mechanism, a vibrator lever, high and low chain balls to position the lever, a force transmitting lever, connections between the vibrator lever and the force transmitting lever, connections between the force transmitting lever and the color selector to position the latter according to the position of the vibrator lever, a regularly moving element, and means interposed between the element and the force transmitting lever to prevent substantial vibration of the latter and the color selector device when the chain balls pass under the vibrator lever.
7. In a multicolor shuttle changing loom, a multicolor magazine for reserve shuttles of different types, a selector to determine which type of shuttle is to be delivered by the magazine, changing shuttle boxes to be moved relatively to the magazine to effect shuttle change, advancing means controlled by the selector to move a selected reserve shuttle toward the changing shuttle boxes, and a single device to cooperate with the selector and the shuttle boxes and effective to insure movement of the shuttle boxes relatively to the magazine and simultaneously actuate the advancing means whenever delivery of a shuttle from the magazine in a shuttle changing operation is to occur.
8. In a multicolor shuttle changing loom, a multicolor magazine for reserve shuttles of different types, a selector to determine which type of shuttle is to be delivered by the magazine, and advance a selected reserve shuttle toward shuttle changing position changing shuttle boxes to be moved relatively to the magazine to effect shuttle change, an actuator for the selector and the change boxes, and means to move the actuator on a shuttle changing beat of the loom, the actuator effective to start movement of the change shuttle boxes relatively to the magazine whenever the selector acts to move a selected reserve shuttle toward shuttle changing position.
9. In a multicolor shuttle changing loom, a multicolor magazine for reserve shuttles of different types, a selector mechanism to determine which type of shuttle is to be delivered by the magazine, changing shuttle boxes to be moved relatively to the magazine to effect shuttle change, a plurality of hooked elements forming part of the selector mechanism, an actuator operatively connected to the change boxes and arranged for cooperation with but one of the hooked elements at a time, said actuator having a movement to shift the change boxes and simultaneously move a hooked element and means to move the actuator on a shuttle changing beat of the loom.
10. In a multicolor shuttle changing loom, a multicolor magazine for reserve shuttles of different types, a selector mechanism to determine

which type of shuttle is to be delivered by the magazine and advance a selected reserve shuttle toward shuttle changing position, changing shuttle boxes to be moved relatively to the magazine to effect shuttle change, an actuator common to the change boxes and selector mechanism, and operating means for the actuator to move the latter at a time of shuttle change, the actuator insuring simultaneous movement of the change boxes relatively to the magazine and movement of the selector mechanism to advance a reserve shuttle on a shuttle changing beat of the loom.

11. In a multicolor shuttle changing loom, a multicolor magazine for reserve shuttles of different types, a color selector, a regularly moving member, change shuttle boxes to move relatively to the magazine on shuttle changing beats of the loom to receive a reserve shuttle, an actuator for the change boxes and the selector, an electro-magnetic device to connect the member and the actuator, a switch to be electrically connected in either of two positions to the electro-magnetic device, an element common to the switch and the selector to position said switch and selector, and means to prevent substantial vibration of the element.

12. In a multicolor shuttle changing loom, a multicolor magazine for reserve shuttles of different types, a color selector, a regularly moving member, change shuttle boxes to move relatively to the magazine on shuttle changing beats of the loom to receive a reserve shuttle, an actuator for the change boxes and the selector, an electro-magnetic device to connect the member and the actuator, a switch to be electrically connected in either of two positions to the electro-magnetic device, an element common to the switch and the selector to position said switch and selector, a pattern mechanism member connected to and positioning the element, and means independent of the pattern mechanism member to prevent substantial vibration of the element and the switch and the color selector should the pattern mechanism member vibrate.

13. In a multicolor shuttle changing loom, a multicolor magazine to hold reserve shuttles of different types, a selector to determine which type of reserve shuttle is to be called and effective to advance a called reserve shuttle toward shuttle changing position, a vibrator lever, spaced pattern elements to determine the position of the vibrator lever, operative connections between the vibrator lever and selector to move the latter by a force derived from the vibrator lever, and means additional to the pattern elements to prevent vibration of the selector when one pattern element moves away from and another element moves under the vibrator lever.

14. In a loom, multicolor weft replenishing mechanism, a selector device for the mechanism, a vibrator lever, a chain to pass under the vibrator lever and having successive high balls to raise and which cause vibration of said lever, a member connected to and movable by the vibrator lever, connections between the member and the selector device, and means to prevent vibration of the member and selector when successive high balls on the chain pass under the vibrator lever.

RICHARD G. TURNER. 70
